Des. 222,535
Patented Nov. 2, 1971

222,535

VEHICLE ROOF-TOP REAR VIEW MIRROR HOUSING

William W. Toy, Bloomfield Hills, and Lynn H. Hodge,
Detroit, Mich.; said Toy assignor to Lewis G. Harmon,
Birmingham, Mich.

Filed July 22, 1969, Ser. No. 20,421
(Filed under Rule 47(a) and 35 U.S.C. 116)

Term of patent 14 years

Int. Cl. D12—16

U.S. Cl. D14—6

FIG. 1 is a top view of the vehicle roof-top rear view mirror housing embodying the present design;

FIG. 2 is a front view of the mirror housing;

FIG. 3 is a rear view of the mirror housing;

FIG. 4 is a side view of the mirror housing as seen from the right side of FIG. 3;

FIG. 5 is a side view of the mirror housing as seen from the left side of FIG. 3;

FIG. 6 is a top front three-quarter view perspective of the mirror housing; and

FIG. 7 is a bottom rear three-quarter view perspective of the mirror housing.

We claim:

The ornamental design for a vehicle roof-top rear view mirror housing, as shown.
